United States Patent Office

Des. 194,604
Patented Feb. 19, 1963

194,604

FREQUENCY STANDARD

Joseph J. Caldwell, Jr., Rolling Hills, Calif., assignor to
Space Technology Laboratories, Inc., Los Angeles,
Calif., a corporation of Delaware

Filed Apr. 3, 1961, Ser. No. 64,579

Term of patent 14 years

(Cl. D26—5)

FIG. 4

FIGURE 1 is a front perspective view of a frequency standard, showing my new design;

FIGURE 2 is a side elevation view thereof;

FIGURE 3 is a back elevation view thereof; and

FIGURE 4 is an enlarged perspective view of a portion of FIGURE 1 and showing one of the corner inserts in the front panel and the band about the cabinet.

I claim:

The ornamental design for a frequency standard, substantially as shown and described.
